UNITED STATES PATENT OFFICE.

DANIEL R. SCHOLES, OF CHICAGO, ILLINOIS, ASSIGNOR TO AERMOTOR COMPANY, OF CHICAGO, ILLINOIS, A CORPORATION OF ILLINOIS.

ENGINE.

987,177.

Specification of Letters Patent. Patented Mar. 21, 1911.

Application filed March 26, 1909. Serial No. 485,984.

To all whom it may concern:

Be it known that I, DANIEL R. SCHOLES, citizen of the United States, residing at Chicago, in the county of Cook and State 5 of Illinois, have invented a certain new and useful Improvement in Engines, of which the following is a full, clear, concise, and exact description, reference being had to the accompanying drawings, forming a part of 10 this specification.

My invention relates to engines and, in particular, to the governing mechanism thereof which is of such a character as to make the invention of especial utility when 15 adapted to hydro-carbon engines.

Difficulty has been hitherto experienced in properly governing the speed of hydro-carbon engines, and particularly those of the gasolene type, owing to vibration and non- 20 uniform propulsive action which occasion incalculable effect upon the governing mechanism due to inertia.

It is an object of my invention to remove the influence of inertia from the governing 25 mechanism as far as is practicable and desirable, in order that such governing mechanism may, in the main, be limited to the action of centrifugal force thereupon.

In the preferred embodiment of my invention, the governing mechanism includes 30 an actuating member responsive to centrifugal force and mounted to swing upon an element rotatively driven by the engine and in a plane transverse to the 35 plane of rotation of said rotatively driven element, this arrangement largely eliminating the effect of inertia upon the governing mechanism. This actuating member is preferably pivotally mounted between its ends 40 upon the rotatively driven element, which may be the fly-wheel, there being desirably a spring operating upon one end of the actuating member to hold the actuating member idle when the engine does not exceed a predetermined speed, said member being 45 weighted upon its other end so as to respond to centrifugal force when the engine exceeds the predetermined speed.

A common method of governing the speed 50 of hydro-carbon engines, particularly those of the gasolene type resides in delaying the closure of the exhaust valves when the engines exceed their predetermined speeds, to which end the governing mechanisms include detaining mechanisms which are

caused to operate upon the exhaust valve structures, when the engines exceed predetermined speeds, to engage the exhaust valve structures to hold the exhaust valves open, these detaining mechanisms being removed 60 out of range with the exhaust valve structures when the engines do not exceed predetermined speeds. In practicing my invention, I use a detaining mechanism as a part of the governing mechanism, for the purpose stated, an element of the detaining mechanism desirably being positively moved by the actuating member whether such member is responding to centrifugal or spring force. The actuating member and the element of the detaining mechanism moving therewith have characteristics of construction and arrangement, as will appear, whereby the effect of inertia, as a disturbing factor, is further removed. 75

I will explain my invention more particularly by reference to the accompanying drawings, showing the preferred embodiment of the invention, in which—

Figure 1 is a side view with parts broken away. Fig. 2 is a sectional view on line 2 2 of Fig. 1. Fig. 3 is a sectional view on line 3 3 of Fig. 2. Fig. 4 is a sectional view on line 4 4 of Fig. 2. Fig. 5 is a plan view 80 of a portion of the exhaust valve operating mechanism shown in association with the exhaust valve.

Like parts are indicated by similar characters of reference throughout the different figures. 90

A well known type of gasolene engine is illustrated, requiring in general, no detailed description. The exhaust valve structure shown includes a well known form of exhaust valve, an extension *a* of the exhaust valve stem extending along the working cylinder *b*, a rocker arm *c* carrying a cam roller *d*, and an abutment plate *e* adapted for separable engagement with the detaining mechanism under conditions to be described. When the engine does not exceed its predetermined speed, the cam roller *d* is maintained in constant engagement with the cam *f* by the spring mechanism *g*, the cam causing recurrent opening movements of the exhaust valve, all as is well understood. When the engine exceeds the predetermined speed, the element *h* of a detaining mechanism comprised within a governing mechanism, is brought into the path of movement of the 100 110

abutment plate *e* to hold the exhaust valve structure against the action of the spring mechanism *g*, whereby the exhaust valve is sufficiently held open until the speed has become properly reduced whereupon the elements *e* and *h* are separated to restore the valve structure to its normal relation with the cam *f*. The cam *f* travels with a gear wheel *k* that is in mesh with a gear wheel *l* mounted upon the main shaft *n* of the engine.

Broadly speaking, the purposes and functions of the parts thus far specifically described in connection with the accompanying drawings are well known to those skilled in the art.

In carrying out the preferred embodiment of my invention, I pivot an actuating member *o*, constituting a part of the governing mechanism, upon an element rotatively driven by the engine, such rotatively driven element preferably being the fly-wheel *p*. The plane of movement of the actuating element is transverse to the plane of movement of the fly-wheel for the reason which has been stated. The actuating member is weighted at one side of its pivot *q* to respond to centrifugal force, and has its end on the other side of said pivot connected with one end of the spring *r*, the other end of which is anchored to a peripheral portion of the fly-wheel. The latter end of the actuating member *o* is in flexible but positive connection with an element *s* of the detaining mechanism, whereby said element *s* is moved whenever said member *o* responds to centrifugal or spring force. In the preferred embodiment of the invention, the element *s* surrounds the shaft *n* and has a circular periphery that is caused to be co-axial with the shaft *n* by the spring *r* when the engine is not running above predetermined speed and which is caused to be eccentric with respect to the shaft when the member *o* responds to centrifugal force, an opening *t* in the disk *s* affording passage for the shaft *n*, this opening being sufficiently elongated and so positioned that the shaft will limit the movement of the element *s* by the spring *r* to a position in which the periphery of the element *s* will be concentric with the shaft *n* and will limit the movement of said element *s* in the reverse direction due to the action of centrifugal force on the member *o* to give the desired degree of eccentricity to the periphery of the element *s* with respect to the shaft *n*. The element *s* thus constitutes a detaining mechanism portion which is rotated by the engine and which moves in a plane parallel with the fly-wheel; that is, the said detaining mechanism portion moves transversely to the axis of the fly-wheel. The element *h* of the detaining mechanism is complementary to the element *s* and is in traveling engagement

with the curved or peripheral surface thereof, preferably by means of a roller *u* carried upon the lower end of the element *h*, this engagement being maintained by a spring *v* or other suitable means. The element *h* is provided with a stationary pivot between its ends. When the element *s* is concentric with the shaft *n*, the upper and forward end of the element *h* is thrown out of line with the reciprocating abutment *e*. When, however, the speed of the engine exceeds its predetermined rate, the roller *u*, then riding upon what has become the eccentric *s*, will throw the upper and forward end of the element *h* into line with the abutment plate *e*, the closure of the exhaust valve being sufficiently delayed or retarded to secure the desired speed regulation as a consequence of the engagement of the elements *e* and *h*.

I have thus provided an improved governing mechanism which includes the actuating member *o* and the detaining mechanism comprising the elements *s* and *h* operating as and for the purpose set forth. In order to relieve the detaining mechanism as far as possible of the influence of inertia, I cause the element *s* thereof to move in a fixed plane with respect to the fly-wheel *p* so as to eliminate movement of the element *s* longitudinally of the axis of rotation of said fly-wheel. This result is preferably accomplished by causing said element to have abutment on one side against the hub of the fly-wheel and abutment upon the other side against a face of a gear wheel *l*, the wheels *p* and *l* being fixed upon the shaft *n*. In order further to relieve the structure from the disturbing influence of inertia, I cause the combined weight of the actuating member *o* and the portion of the detaining mechanism *s* moving therewith to be substantially equally distributed upon opposite sides of the mounting for the member *o*, whereby substantially equal opposing turning moments due to inertia are set up, centrifugal force acting upon one end of the element *o* tending to turn it in one direction about its axis of movement and operating upon the other end of said element *o* tending to turn it in reverse direction about its axis of movement.

While I have herein shown and particularly described the preferred embodiment of my invention, I do not wish to be limited to the precise details of construction shown, as changes may readily be made without departing from the spirit of my invention.

Having thus described my invention, I claim as new and desire to secure by Letters Patent:—

1. An engine having a speed governing mechanism which includes an element rotatively driven by the engine, exhaust valve detaining mechanism containing a part rotating with said rotatively driven element and movable with respect to the rotatively

driven element, a member operating upon said part of the detaining mechanism mounted to swing upon said rotatively driven element in a plane transverse to the 5 plane of rotation of the rotatively driven element and moving in response to centrifugal force arising when the engine exceeds predetermined speed, to cause operation of the detaining mechanism through its aforesaid 10 part to hold the exhaust valve open, and means whereby said part of the detaining mechanism is prevented from having material movement relative to the rotatively driven element longitudinally of the axis 15 of rotation of said rotatively driven element to avoid the effect of inertia thereupon when the engine is shaken longitudinally of said axis, the combined weight of said member and the part of the detaining 20 mechanism moving therewith being substantially equally distributed upon both sides of the mounting of said member, whereby substantially equal opposing turning moments due to inertia are set up.

25 2. An engine having a speed governing mechanism which includes an element rotatively driven by the engine, exhaust valve detaining mechanism containing a part rotating with said rotatively driven element 30 and movable with respect to the rotatively driven element, a member operating upon said part of the detaining mechanism mounted to swing upon said rotatively driven element in a plane transverse to the plane of 35 rotation of said rotatively driven element and moving in response to centrifugal force arising when the engine exceeds predetermined speed, to cause operation of the detaining mechanism through its aforesaid 40 part to hold the exhaust valve open, the combined weight of said member and the part of the detaining mechanism moving therewith being substantially equally distributed upon both sides of the mounting 45 of said member, whereby substantially equal opposing turning movements due to inertia are set up.

3. An engine having a speed governing mechanism which includes an element rotatively driven by the engine, exhaust valve detaining mechanism containing a part rotating with said rotatively driven element and movable with respect to the rotatively driven element, a member operating upon 50 said part of the detaining mechanism mounted to swing upon the rotatively driven element and moving in response to centrifugal force arising when the engine exceeds predetermined speed, to cause operation of the 55 detaining mechanism through its aforesaid part to hold the exhaust valve open, the combined weight of said member and the part of the detaining mechanism moving therewith being substantially equally distributed upon both sides of the mounting 60 65

of said member whereby substantially equal opposing turning moments due to inertia are set up, and means whereby said part of the detaining mechanism is prevented from having material movement relative to the rotatively driven element to avoid the effect of inertia thereupon when the engine is shaken longitudinally of said axis. 70

4. An engine having a speed governing mechanism which includes an element rotatively driven by the engine, exhaust valve detaining mechanism containing a part rotating with said rotatively driven element and movable with respect to the rotatively driven element, and a member operating upon said part of the detaining mechanism mounted to swing upon the rotatively driven element and moving in response to centrifugal force arising when the engine exceeds predetermined speed, to cause the 80 operation of the detaining mechanism through its aforesaid part to hold the exhaust valve open, the combined weight of said member and the part of the detaining mechanism moving therewith being substantially equally distributed upon both sides of the mounting of said member whereby substantially equal opposing turning moments due to inertia are set up. 85

5. An engine having a speed governing mechanism which includes an element rotatively driven by the engine, exhaust valve detaining mechanism containing a part rotating with said rotatively driven element and movable with respect to the rotatively driven element across its axis of rotation and a second part in traveling engagement with the aforesaid part of the detaining mechanism and interposed between the same and the exhaust valve of the engine, a member capable of operating upon the first aforesaid part of the detaining mechanism and mounted to swing upon the rotatively driven element in a plane transverse to the plane of rotation of said rotatively driven element and capable of moving in response to centrifugal force arising when the engine exceeds predetermined speed, to cause operation of the detaining mechanism through its first aforesaid part to hold the exhaust valve open, and a spring adapted sufficiently to oppose the action of centrifugal force upon said member when the engine is not exceeding its predetermined speed to free the detaining mechanism from the exhaust valve. 95 100 105 110

6. An engine having a speed governing mechanism which includes an element rotatively driven by the engine, exhaust valve detaining mechanism containing a part movable across the axis of rotation of said rotatively driven element, and a member capable of operating upon said part of the detaining mechanism and mounted to swing upon said rotatively driven element in a 120 125 130

plane transverse to the plane of rotation of said rotatively driven element and capable of moving in response to centrifugal force arising when the engine exceeds predetermined speed, to cause operation of the detaining mechanism through its aforesaid part to hold the exhaust valve open.

7. An engine having a speed governing mechanism which includes an element rotatively driven by the engine, exhaust valve detaining mechanism containing a part rotating with said rotatively driven element and movable across its axis of rotation, a member capable of operating upon said part of the detaining mechanism and mounted to swing upon said rotatively driven element in a plane transverse to the plane of rotation of said rotatively driven element and capable of moving in response to centrifugal force arising when the engine exceeds predetermined speed, to cause the operation of the detaining mechanism through its aforesaid part to hold the exhaust valve open, and a spring adapted sufficiently to oppose the action of centrifugal force upon said member when the engine is not exceeding

predetermined speed, to free the detaining mechanism from the exhaust valve.

8. An engine having a speed governing mechanism which includes an element rotatively driven by the engine, exhaust valve detaining mechanism containing a part rotating with said rotatively driven element and movable with respect to the rotatively driven element across its axis of rotation, and a member capable of operating upon said part of the detaining mechanism and mounted to swing upon said rotatively driven element in a plane transverse to the plane of rotation of said rotatively driven element and capable of moving in response to centrifugal force arising when the engine exceeds predetermined speed, to cause operation of the detaining mechanism through its aforesaid part to hold the exhaust valve open.

In witness whereof, I hereunto subscribe my name this 19th day of March A. D., 1909.

DANIEL R. SCHOLES.
